CHAIR

Phillip K. Raiford, Memphis, Tenn., assignor to Shoe House, Inc., Memphis, Tenn., a corporation of Tennessee

Filed Oct. 20, 1965, Ser. No. 87,641

Term of patent 14 years

(Cl. D15—1)

FIG. 1 is a view in three-quarter front perspective of a chair embodying my new design.

FIG. 2 is a side elevation thereof.

FIG. 3 is a rear elevation thereof.

FIG. 4 is a plan view thereof.

The side of the chair not shown is a mirror image of, and hence the same in appearance as, the side which is illustrated.

I claim:

The ornamental design for a chair, as shown and described.
